EJECTION MEANS FOR REVOLVERS

Charles Edward Rowe, Athol, Mass., assignor to
Harrington & Richardson Arms Company, Worcester, Mass., a corporation of Massachusetts

Application December 27, 1949, Serial No. 135,075

3 Claims. (Cl. 42—68)

1

This invention relates to manual ejection means for the fired shells of revolvers particularly of the solid frame type, in which the cylinder must be removed in order to eject the spent cartridge shells.

The principal object of the invention resides in the provision of ejection means for a solid frame revolver or the like, comprising a center pin on which the cylinder rotates as the revolver is fired to present a new cartridge to the hammer and barrel, said pin being easily removable allowing the cylinder to be dropped out of the solid frame, and said cylinder having ejection means therein to be manually actuated by said pin but only when both pin and cylinder are completely removed from the revolver.

Another object of the invention resides in the provision of ejection means as above stated, said ejection means being removable from the cylinder in one rotative position only thereof, said ejection means comprising an indented plate adapted to underlie the rims of rim fire cartridges and including a hollow cylinder thereon having a circumferential groove adjacent an end thereof opposite the plate, said cylinder being flat on one side from the plate to the groove, and said groove forming a shoulder which is flat at a side opposite the flattened area of the ejector cylinder, in combination with means in the revolver cartridge cylinder forming a central chamber receiving the ejection cylinder, said chamber having a flattened boss at one end allowing entrance of said flange in one rotative position only of the ejection means, said boss allowing the ejection means to rotate when aligned with the said groove and the flattened part of the ejection cylinder allowing the latter to slide down into the cartridge cylinder into operative position therein.

Other objects and advantages of the invention will appear hereinafter.

Reference is to be had to the accompanying drawings in which

Fig. 1 is a view in side elevation of a revolver according to the present invention, parts being broken away;

Fig. 2 is an enlarged view of the cylinder pin and latching means therefor;

Fig. 3 is a cross section through the cylinder illustrating the action of the ejecting means;

Fig. 4 is a rear elevational view of the cylinder showing the same partly loaded;

Fig. 5 is a front view in elevation of the ejecting device; and

Fig. 6 is a front view in elevation of the revolver with the grip removed.

2

The present invention relates mainly, but not exclusively, to solid frame revolvers and this application is therefore illustrated with relation to a revolver having a solid frame 10 in which there is provided a cylinder opening for cartridge cylinder 12, which cylinder is removable only laterally, but to either side of frame 10. The frame 10 is, of course, provided with barrel 14, trigger 16, hammer 18 and grip 20, as is conventional.

Solid frame 10 is provided with a pair of semi-circular laterally extending cylinder abutment plates 22 and 24 to the rear of the cylinder, plate 24 having slot 26 for loading the cylinder 12 cartridge by cartridge, as the cylinder is rotated; but, alternatively, the cylinder may be removed, loaded, and replaced as is apparent.

The cylinder 12 is provided with a separable pin 28 on which it rotates as advanced by the trigger or hammer action as is well known in the art, pin 28 serving as a center shaft. The frame 10 is provided with a small notch as for instance, at 30 to receive the tip 32 of the pin 28; and axially across the cylinder opening, it is provided with a passage 34, notch 36 and passage 34 providing holding means axially located relative to cylinder 12 mounting the latter rotatively. Pin 28 is held in position by means of a pivoted latch 36 taking into a notch 38 and having a spring 40 located in the frame 10. Latch 36 has an outwardly extending portion 42 to be engaged by the finger of the operator whereby to depress the same against the action of spring 40 and rotate latch 36 sufficiently to disengage it from pin 28 whereupon the latter may be withdrawn and the cylinder 12 dropped out.

Cylinder 12 is provided with a series of small bores 44 receiving cartridges 46 and at its rear face it is provided with a depression 48 extending part way into the bores, and shaped to receive an ejector plate 50 which is provided with a series of small peripheral semi-circular cartridge-receiving recesses, the ejector plate fitting into the depression 48 and completing the same to form stops for the rims of the cartridges 46. As is plainly seen, it is merely necessary to move ejector plate 50 outwardly of the cylinder 12, see Fig. 3, to remove the empty cartridge cases 52, all of these cartridge cases being removed simultaneously.

The ejector plate 50 is integrally joined to a central sleeve or tubular member 52, the bore of which is formed with an annular shoulder 54 at one end to receive shoulder 56 of the pin 28. Hence, all that it is necessary to do to extract

the cartridges is to actuate the latch 36 as above described, remove the pin 28, drop out cylinder 12, insert pin 28 within the hollow cylinder 52 and move the latter outwardly, as shown in Fig. 3, thus ejecting all of the empty shells.

Pin 28 is then removed from the cylinder 52, the latter is replaced so that plate 50 is located in the depression 48 and the cylinder is then re-loaded and re-inserted in the solid frame 10, thereupon being held in position by pin 28.

The tubular member 52 is cut away or flattened along one side as at 58 from plate 50 to a circumferential recess or circular groove 60. This groove forms a shoulder or flange 62 which is flattened diametrically oppositely as at 64 from the flat 58. The central chamber 52 of cylinder 12 is provided with a lug or the like 66 at the forward end thereof and this lug or projection prevents complete removal of the ejector device when it is pushed to the left in Fig. 3, by the pin 28 because of the abutment of shoulder 62 therewith. In addition, the flat 58 rides on this boss and the same prevents the ejector cylinder 52 from rotating so that the ejector plate 50 always must fit into the notch 58 in exactly the same way.

In order to extract the ejector, it is merely necessary to withdraw the same until boss 66 aligns with groove 60 and in this position, the ejector is allowed to rotate. A 180° turn will then bring flat portion 64 in alignment with boss 66 whereupon the entire ejector is removed and may be replaced in similar manner.

It will be seen that this invention provides an inexpensive firearm of the solid frame type having a convenient and easy shell ejection device in which the cylinder center pin is manually utilized to extract all of the empty shells at once.

Having thus described my invention and the advantages thereof, I do not wish to be limited to the details herein disclosed otherwise than as set forth in the claims, but what I claim is:

1. In a solid frame revolver formed with a cylinder opening communicating with the barrel, a shell cylinder in said opening, said cylinder having an axial bore and an abutment at the inner end of said bore, ejector means including an ejector plate engageable with the rim of shells carried by said cylinder and a tubular member connected with said plate and slidable axially within the bore of said cylinder from shell-load- 40 45 50

ing position to shell-ejecting position, the inner surface of said tubular member having a shoulder portion, the outer surface of said tubular member having a longitudinally cut away portion to accommodate said abutment so as to permit said axial movement but oppose rotational movement of said tubular member relative to said cylinder, the outer end of said tubular member having a projecting part engageable with said abutment when said tubular member is slid to shell-ejecting position, thereby to prevent removal of said ejector means from said cylinder, and a cylinder pin projecting through said frame and extending axially through said tubular member so as to support said cylinder for rotation, said pin being removable to permit detachment of said cylinder from said frame and when detached said pin being engageable with said shoulder portion to operate said ejector means.

2. A revolver as set forth in claim 1, wherein said tubular member is circumferentially recessed between its outer end and said projecting part so that said tubular member may be rotated when in shell-ejecting position, thereby to permit said ejector means to be separated from said cylinder.

3. A revolver as set forth in claim 1, wherein said tubular member is cylindrical and the longitudinally cut away portion is in the shape of a chordal flat, and said abutment is in the form of a segment complementing said chordal flat, and said tubular member is formed with a circumferential groove between its outer end and said projecting part so as to permit rotation of said tubular member when in shell-ejecting position to disengage said abutment and projecting part and permit said ejector means to be separated from said cylinder.

CHARLES EDWARD ROWE.
